UNITED STATES PATENT OFFICE

2,011,170

POWER DRIVEN CAN OPENING MACHINE

George P. Ames, Springfield, Mass.

Application October 5, 1934, Serial No. 747,026

5 Claims. (Cl. 30—3)

My invention relates to improvements in power driven can opening machines, and is in improvement of my can opening machine for which Letters Patent of the United States of America, #1,845,213, were granted to me on February 16, 1932.

An object of the present invention is to provide a can opening machine having means for rotating the can, a knife, a carrier for the knife, a motor for operating the can-rotating means, a switch on the carrier, and operative connecting means between the knife and the switch, whereby when the knife is engaged in the can cover and the can held against its rotating means, the switch will be automatically closed, and, when the knife and can are released, the switch will be automatically opened.

A further object of this invention is to provide, in such a machine, a single operating lever for controlling the knife, the carrier clutch, and the motor control switch, this lever being also instrumental in holding the can against the can-rotating means.

These, and other objects and advantages, will be more completely described and disclosed in the specification, the accompanying drawings, and the appended claims.

Broadly, my invention comprises a platform for supporting a can to be opened, a rotatable, grooved, or toothed driving post, against which the can is held for imparting rotation to the can during the opening operation, a motor, operative connecting means between the motor and the can-driving post, guide posts on either side of the toothed driving post, a carrier member slidably mounted on the guide posts, a clutch on the carrier for engaging the guide posts to hold the carrier in operating position, a knife holder pivotally supported on the carrier, a knife in the holder, a motor control switch on the carrier and operatively engaged by the knife holder, and a lever on the carrier, for operating the clutch and the knife holder, whereby, when the lever is operated to force the knife through the can top and hold the can against the toothed driving post, the switch will be closed by the knife holder.

A preferred embodiment of my invention is illustrated in the accompanying drawings, in which:

Fig. 1 is a front, elevational view of the can opening machine.

Fig. 2 is a vertical, sectional view on the line 2—2 of Fig. 1.

Fig. 3 is a partial, rear view, showing the carrier, the switch, and the knife holder.

Fig. 4 is a plan, sectional view on the line 4—4 of Fig. 1, and

Fig. 5 is a perspective view of the knife holder. Referring now to the drawings in detail, in which like numerals refer to like parts throughout:

A boxlike base member 1 has formed thereon posts 2 to the top 3 of which is removably secured a bearing plate 4. A motor 5, in the base 1, is operatively connected through a speed reducing unit 6, to a toothed driving post 7, rotatably supported between the base 1 and the plate 4. Guide posts 8 are also secured between the base 1 and the plate 4. A carrier member 9 is slidably supported on the guide posts 8, and has pivotally secured thereto a clutch plate 10. A knife holder 11 is pivotally secured by pivot pins, or screws 12, to the carrier 9, and contractile springs 13, secured to the knife holder 11 and clutch plate 10, normally retains the clutch plate 10 in engagement with the post 8 to prevent movement of the carrier 9 and also normally holds a knife 14, secured in the knife holder 11, in inoperative position, relative to the driving post 7. A motor control switch 15, secured on the back of the carrier 9, is provided with a spring-controlled operating lever 16, which is normally held in open circuit position, as indicated by the dotted lines in Fig. 3, and a projecting portion 17 on the holder 11 is positioned to engage the end 18 of the lever 16.

An operating lever 18 is pivotally secured on the carrier 9 in operative relation to the knife holder 11 and the clutch plate 10, and is normally held in inoperative position, as indicated in dotted lines at 18' in Fig. 1, by the action of the springs 13, which tend to pull the clutch plate 10 and knife holder 11 toward each other. When the operating lever 18 is raised to the vertical position, indicated at 18'', in Fig. 1, a cam surface 19 on the lever 18 engages a cam surface 20 on the clutch plate 10 to release the clutch plate 10 from engagement on the guide posts 8. When the lever 18 is depressed into the position, indicated at 18, in full line in Fig. 1, the knife 14 is forced downwardly and inwardly, piercing the top 21 of a can 22, placed on the base 1 and forcing the side 23 of the can 22 against the toothed driving post 7, as indicated in Fig. 2. The clutch plate 10 is now moved on the rods 8.

At the same time, the rear portion 17 of the holder is raised, thus actuating the spring-controlled operating lever 16 and closing the circuit to the motor.

The cycle of operation is as follows:—

A can 22, to be opened, is placed on the base 1, the lever 18 raised from its normal position 18', to release the clutch 10 from the guide posts 8; the carrier member 9 is now raised to clear the can 22, and the can 22 placed in position with its side 23 engaging the toothed drive shaft, or post 7. The carrier is then lowered, until the knife 14 rests on the top 21 of the can 22. The lever 18 is then moved into the operating position, shown in full lines in Fig. 1, for forcing the knife 14 through the cover 21. At the start of this movement, the clutch plate 10 is released and forced into engagement with the posts 8 by the springs 13, thus holding the carrier 9 firmly against vertical movement. Then, the knife 14 is forced through the cover 21 and, by engagement with the inside, or inner surface of the can side 23, which forces the wall 23 of the can against the toothed drive post 7. The switch 15 is now closed by the holder 11 engaging the lever 16 and the can revolved against the knife 14 by the motor 5, acting through the speed reducer 6 on the toothed drive shaft 7. When the cover 21 is cut out of the can 22, the lever 18 is released by the operator and moved into the neutral position 18' by the springs 13, thus releasing the switch lever 16 and permitting the switch lever 16 to open the motor circuit, stopping the motor and drive shaft 7. The coverless can may then be released, or removed from the base 1, by raising the lever 18 to the position 18'' and lifting the carrier 9 and its co-operating parts out of the way. Pins, or studs 24, on the carrier 9, limit the movements of the lever 18.

The knife holder 11, it will be noticed, is formed with an opening 11', in which is located the toothed drive post 7.

What I claim is:—

- 40 1. In a motor-driven can opening machine, a knife, a holder for the knife, a movable carrier for the knife holder and pivotally connected to the knife carrier, a motor control switch on the carrier, and operative connecting cam means between the pivoted holder for the knife and the switch for closing the switch when the knife is in operative position.
- 45 2. In a motor-driven can opening machine, a knife, a movable carrier member, a knife holder pivotally supported on the carrier member, a motor control switch on said carrier member in

operative relation with said holder, an operating lever on said carrier member in operative contact with said holder, whereby when said holder is actuated by said lever, said switch will be closed by said holder.

5 3. In a machine for severing the cover portion of a metallic can, a cutter, a movable carrier for the cutter, a support for the can, a toothed rotatable member for rotating the can, a motor for operating the rotatable member, lever means 10 on the movable carrier for the cutter for simultaneously forcing the cutter through the cover of the can and the can against the toothed rotatable member, a motor control switch on the movable carrier for the cutter, the lever means 15 serving to close the switch when the cutter is forced through the cover of the can, and to open the switch when the lever means is released at the end of the cutting operations.

4. In combination, in a motor-driven can opening machine, a receiving platform, means for rotating the can, guide rods, a carrier on the guide rods, a knife, a knife support pivotally connected to the carrier, spring means for normally and automatically retaining the carrier 25 on the guide rods, a switch on the carrier, an operating lever on the carrier having a cam surface for operating the spring-controlled means for releasing the carrier on the guide rods, when in one position and said lever serving to closing 30 the switch and forcing the knife through the cover of the can when in another position, and said spring means serving to return the operating lever to its normal position for permitting the carrier and its knife support to be retained on 35 the guide posts, as described.

5. In combination, in a motor-driven can opening machine, a support for the can, means for rotating the can, a carrier, guide means for the carrier, a knife holder pivotally supported in the 40 carrier, a switch on the carrier, clutch means for automatically retaining the carrier positioned on the guide means, a lever for controlling the clutch means of the carrier for causing the clutch means on the guide means to grip the guide means 45 to permit the knife to be forced through the cover of the can and against the can-rotating means for closing the switch to the motor and for opening the switch when the lever is released at the end of the cutting operation.

50 GEORGE P. AMES.
